DESIGN FOR A COMBINATION CURTAIN ROD AND SUSPENDING MEANS

Edith Weis, New York, N. Y.

Application March 10, 1944, Serial No. 112,859

Term of patent 14 years

(Cl. D21—1)

To all whom it may concern:

Be it known that I, Edith Weis, a citizen of the United States, residing at New York city, in the county of New York and State of New York, have invented a new, original, and ornamental Design for a Combination Curtain Rod and Suspending Means, of which the following is a specification, reference being had to the accompanying drawing, forming part thereof.

In the drawing

Fig. 1 is a perspective view of a combination curtain rod and suspending means showing my new design;

Fig. 2 is a top plan view thereof.

Fig. 3 is a side elevational view of the same.

I claim:

The ornamental design for a combination curtain rod and suspending means, substantially as shown,

EDITH WEIS.
